UNITED STATES PATENT OFFICE

167,909

ROTARY BRUSH TO SHINE SHOES OR SIMILAR ARTICLE

Vincent A. Restagno, Watertown, Mass.

Application January 8, 1951, Serial No. 13,709

Term of patent 7 years

(Cl. D9—2)

To all whom it may concern:

Be it known that I, Vincent A. Restagno, a citizen of the United States, residing at Watertown, in the county of Middlesex, in the Commonwealth of Massachusetts, have invented a new, original, and ornamental Design for a Rotary Brush To Shine Shoes or Similar Article, of which the following is a specification, reference being had to the accompanying drawing, forming a part thereof, in which:

Figure 1 is a side elevational view, Figure 2 is a top plan view, and Figure 3 is a rear elevational view of a rotary brush to shine shoes embodying my new design. Both sides are the same as that shown in Figure 1.

I claim:

The ornamental design for a rotary brush to

shine shoes or similar article, substantially as shown and described.

VINCENT A. RESTAGNO.
